UNITED STATES PATENT OFFICE

91,542

DESIGN FOR AN EGG CUP HAVING A TOP

Edward A. Reiser, Columbus, Ohio

Application November 25, 1933. Serial No. 49,874

Term of patent 7 years

To all whom it may concern:

Be it known that I, EDWARD A. REISER, a citizen of the United States, residing in the city of Columbus in the county of Franklin and State of Ohio, have invented a new, original, and ornamental Design for an Egg Cup having a Top, of which the following is a specification, reference being had to the accompanying drawing, forming part hereof.

The figure is a perspective view of an egg cup having a top, showing my new design.

I claim:

The ornamental design for an egg cup having a top, as shown.

EDWARD A. REISER.
